(57) **CLAIM**

The ornamental design for a joint for connecting a pillar and a beam, as shown and described.

DESCRIPTION

FIG. 1 is a front elevational view of the joint for connecting a pillar and a beam showing our new design.

FIG. 2 is a top plan view thereof.

FIG. 3 is a left side elevational view thereof.

FIG. 4 is a right side elevational view thereof.

FIG. 5 is a partially sectional view thereof taken substantially by the arrows 5—5 of FIG. 1.

FIG. 6 is a partially sectional view thereof taken substantially by the arrows 6—6 of FIG. 1.

FIG. 7 is a perspective view thereof showing the state in which the joint is used to connect a cross-shaped sectional pillar and H-shaped sectional beams; and,

FIG. 8 is a perspective view thereof showing the state in which the joint is used to connect an H-shaped sectional pillar and H-shaped sectional beams.
